UNITED STATES PATENT OFFICE

2,156,112

LIQUID DISPENSER

Tunis J. Dykema, Pittsburgh, Pa.

Application June 4, 1938, Serial No. 211,837

8 Claims. (Cl. 221—148)

This invention relates to liquid dispensers and more particularly to dispensers of the general character disclosed in my United States Reissue Letters Patent No. 19,520 and which are adapted to be manipulated by squeezing the bulb between the fingers to eject a considerable proportion of the contents of the bulb and also by depressing a portion of the bulb inwardly with one finger to eject an approximately measured quantity of fluid constituting a comparatively small proportion of the contents of the bulb. To this end the compressible squeezing portion of the bulb is preferably so designed that when squeezed transversely between the fingers it will eject a considerable proportion of its contents and preferably has at its closed end an integral portion so related to the remainder of the compressible squeezing portion of the bulb as to be clearly defined exteriorly of the bulb and being adapted to be depressed by a finger toward the interior of the bulb and in being so depressed to move inwardly of the bulb for the most part independently of the remainder of the compressible squeezing portion of the bulb whereby to eject from the bulb upon substantially complete depression of said portion thereof an approximately measured quantity of fluid constituting a comparatively small proportion of the contents of the bulb.

While my invention is applicable to dispensing devices of various sizes, it is particularly well suited for small size dispensing devices dispensing liquids in amounts of the order of a few drops. Squeezing of the bulb transversely between the fingers in the usual way results in the dispensing of relatively large quantities of liquid which in a small capacity outfit may be, for example, from ten to twenty drops or more. Difficulty is encountered in the dispensing of a single drop and to aid in doing so without dispensing more than one drop at the same time I preferably provide at the closed end of the bulb an integral portion thereof so related to the remainder of the compressible squeezing portion of the bulb as to be clearly defined exteriorly of the bulb and being adapted to be depressed by a finger toward the interior of the bulb and in being so depressed to move inwardly of the bulb for the most part independently of the remainder of the compressible squeezing portion of the bulb whereby to eject from the bulb upon substantially complete depression of said portion thereof an approximately measured quantity of fluid constituting a comparatively small proportion of the contents of the bulb and constituting in general one drop. Such portion of the bulb may be of whatever ca-

pacity may be desired in any particular case, but I find that a capacity of one drop is most useful.

The portion of the bulb above referred to is preferably not substantially greater in area than the area of the tip of a forefinger of average size so as to facilitate operation thereof simply by pressing the same with the forefinger or some other finger. Such portion is also preferably relatively thin as compared with the material of the remainder of the compressible squeezing portion of the bulb.

The bulb preferably has an inward recess in its outer surface for receiving the portion of the top of the cap surrounding the hole therein whereby in normal use the cap and bulb remain locked together as a unit, thus counteracting the tendency to push the bulb out of the cap existing when the above mentioned portion of the bulb is depressed by a finger. The bulb is preferably generally cylindrical for the greater part of its extent and its closed end is preferably generally dome shaped. Preferably the inner surface of the compressible squeezing part of the bulb is generally cylindrical for the greater part of its extent and is generally dome shaped at the closed end of the bulb, the radius of the dome being of the same order as the radius of the generally cylindrical portion of such inner surface and the dome being substantially smoothly continuous with respect to the cylindrical portion.

Other details, objects and advantages of the invention will become apparent as the following description of a present preferred embodiment thereof proceeds.

In the accompanying drawing I have shown a present preferred embodiment of the invention, in which

Figure 1 is a central vertical transverse cross-sectional view through a bottle equipped with a combination closure and liquid dispenser;

Figure 2 is an enlarged cross-sectional view of the dispenser bulb;

Figure 3 is an enlarged cross-sectional view of the closure or cap for the bottle; and

Figure 4 is a perspective view showing the dispenser of Figure 1 used for dispensing a single drop of liquid.

Referring now more particularly to the drawing, there is shown a bottle 2, which may, for example, be a medicine prescription bottle of any suitable capacity. The bottle 2 has a neck 3 which adjacent its lip 4 is provided exteriorly with screw threads 5 for the reception of a screw cap 6. The cap 6 has in its top 7 a circular opening 8 through which passes a resilient hollow

bulb 9, preferably of rubber. The bulb 9 comprises a squeezing portion 10 of which the upper part 11 is of dome shape and the lower part 12 is generally cylindrical. The bulb has an opening 13 communicating with its interior 14, the opening being surrounded at its outer extremity by an annular lip 15 shown as being of generally conical shape adapted when the device is applied to the bottle to lie against the bottle lip 4 to seal the bottle as shown in Figure 1. The bulb has an inward recess 16 in its outer surface for receiving the portion 17 of the top of the cap surrounding the hole 8 therein. The bulb is inserted into the cap and snapped into place with the annular portion 17 of the cap entering the recess 16 whereby in effect to lock the bulb and cap together as a unit.

The outside diameter of the lower part 12 of the bulb is substantially greater than the diameter 20 of the hole 8 in the cap 6, thus counteracting the tendency to push the bulb out of the cap existing when the closed end of the bulb is depressed by a finger as will presently be described.

The opening 13 in the bulb has an enlarged 25 portion 18 receiving a flange 19 formed at the upper extremity of a hollow transparent liquid receptacle shown as being in the form of a glass tube 20. The tube 20 has an opening 21 at its lower end through which to receive and discharge 30 the liquid contents of the bottle 2.

When the generally cylindrical part 12 of the squeezing portion 10 of the bulb 9 is squeezed between the fingers in a direction transversely of the direction of the length of the dispensing tube 35 20 it will eject a considerable proportion of its contents, as such squeezing can flatten out the squeezing portion of the bulb rather completely. The dome-shaped portion 11 at the closed end of the bulb is an integral portion of the material of 40 the bulb and is shown as being relatively thin as compared with the material of the generally cylindrical portion of the bulb. The dome-shaped portion 11 is adapted to be depressed by a finger toward the interior of the bulb as shown in Figure 4 and in being so depressed to move inwardly 45 of the bulb for the most part independently of the relatively thick walled portion of the bulb whereby to eject from the bulb upon substantially complete depression of said portion thereof 50 an approximately measured quantity of fluid constituting a comparatively small proportion of the contents of the bulb. This approximately measured quantity may for convenience be one drop or minim. Figure 4 indicates the ejection 55 of one drop or minim of the contents of the dispenser upon complete inward depression of the portion 11 of the bulb. The provision of the inward recess 16 in the outer surface of the bulb for receiving the portion 17 of the top of the cap surrounding the hole 8 therein effectively counteracts the tendency to push the bulb out of the cap existing when the portion 11 of the bulb is depressed by a finger.

The inner surface 22 of the compressible 65 squeezing part 10 of the bulb is generally cylindrical for the greater part of its extent and is generally dome-shaped at the closed end of the bulb, the radius of the dome being of the same order as the radius of the generally cylindrical 70 portion of such inner surface and the dome being substantially smoothly continuous with respect to the cylindrical portion. In the form shown in the drawing the radius of the cylindrical portion and the radius of the dome are the same. The 75 wall thickness of the bulb at the cylindrical por-

tion is substantially greater than at least a portion of the dome so that when the cylindrical portion is squeezed between the fingers in a direction generally transversely of its axis it will eject a considerable proportion of its contents. The portion of the bulb having the relatively thin wall is adapted to be depressed by a finger toward the interior of the bulb as above pointed out and in being so depressed to move inwardly of the bulb for the most part independently of the relatively 10 thick walled portion of the bulb whereby to eject from the bulb upon substantially complete depression of said portion thereof an approximately measured quantity of fluid constituting a comparatively small proportion of the contents of 15 the bulb as above mentioned.

The portion of the bulb which upon inward depression results in ejection from the bulb of an approximately measured quantity of fluid constituting a comparatively small proportion of 20 the contents of the bulb is preferably shaped so as to be clearly defined exteriorly of the bulb so that the point at which to depress the bulb with the finger may readily be ascertained. Such portion is adapted to be depressed by a finger toward 25 the interior of the bulb and in being so depressed to move inwardly of the bulb for the most part independently of the remainder of the compressible squeezing portion of the bulb. Such portion is preferably not of substantially greater area 30 than the tip of a forefinger of average size. This facilitates its operation in the manner shown in Figure 4.

In my copending application Serial No. 211,836, filed of even date herewith, there is disclosed a 35 combination container closure and liquid dispenser comprising a bulb having an inward recess in its outer surface for receiving the portion of the top of the cap surrounding the hole therein, but there accomplishing an entirely different 40 result.

While I have shown and described a present preferred embodiment of the invention, it is to be distinctly understood that the same is not limited thereto but may be otherwise variously embodied 45 within the scope of the following claims.

I claim:

1. A liquid dispenser comprising a unitary resilient hollow bulb having an opening therein, a dispensing tube connected with the bulb adjacent 50 said opening, the bulb being generally cylindrical for the greater part of its extent generally in the direction of the length of the dispensing tube and having at least a substantial portion of said generally cylindrical part thereof exposed in a direction transversely of the direction of the length of the dispensing tube and sufficiently flexible that when squeezed between the fingers it will eject a considerable proportion of its contents, the bulb having at its closed end an integral portion of the 55 material thereof which is relatively thin as compared with the material of the generally cylindrical portion of the bulb, said portion of the bulb being adapted to be depressed by a finger toward the interior of the bulb and in being so depressed 60 to move inwardly of the bulb for the most part independently of the relatively thick walled portion of the bulb whereby to eject from the bulb upon substantially complete depression of said portion thereof an approximately measured quantity of fluid constituting a comparatively small 65 proportion of the contents of the bulb.

2. A combination container closure and liquid dispenser comprising a cap for a container such as a bottle or the like, the cap having a hole in 70

its top, a unitary resilient hollow bulb having an opening therein, a dispensing tube connected with the bulb adjacent said opening, the bulb passing through said hole in the top of the cap and having a compressible squeezing part disposed outwardly of the cap which is generally cylindrical for the greater part of its extent generally in the direction of the length of the dispensing tube and has at least a substantial portion of said generally cylindrical part thereof exposed in a direction transversely of the direction of the length of the dispensing tube and sufficiently flexible that when squeezed between the fingers it will eject a considerable proportion of its contents, the bulb having at its closed end an integral portion of the material thereof which is relatively thin as compared with the material of the generally cylindrical portion of the bulb, said portion of the bulb being adapted to be depressed by a finger toward the interior of the bulb and in being so depressed to move inwardly of the bulb for the most part independently of the relatively thick walled portion of the bulb whereby to eject from the bulb upon substantially complete depression of said portion thereof an approximately measured quantity of fluid constituting a comparatively small proportion of the contents of the bulb, the bulb having an inward recess in its outer surface for receiving the portion of the top of the cap surrounding the hole therein whereby in normal use the cap and bulb remain locked together as a unit, thus counteracting the tendency to push the bulb out of the cap existing when said portion of the bulb is depressed by a finger.

3. A unitary resilient hollow bulb for liquid dispensers, such bulb having an opening therein adapted for cooperation with a dispensing tube and having a compressible squeezing part whose inner surface is generally cylindrical for the greater part of its extent and which inner surface is generally dome shaped at the closed end of the bulb, the radius of the dome being of the same order as the radius of the generally cylindrical portion of such inner surface and the dome being substantially smoothly continuous with respect to the cylindrical portion, the wall thickness of the bulb at the cylindrical portion being substantially greater than at at least a portion of the dome, the cylindrical portion being sufficiently flexible that when squeezed between the fingers in a direction generally transversely of its axis it will eject a considerable proportion of its contents, the portion of the bulb having the relatively thin wall being adapted to be depressed by a finger toward the interior of the bulb and in being so depressed to move inwardly of the bulb for the most part independently of the relatively thick walled portion of the bulb whereby to eject from the bulb upon substantially complete depression of said portion thereof an approximately measured quantity of fluid constituting a comparatively small proportion of the contents of the bulb.

4. In combination, a container such as a bottle or the like having an opening communicating with its interior and surrounded at its outer extremity by an annular lip, a cap fitting over said lip and having a hole in its top, means for fastening the cap to the container, and a dispensing device comprising a hollow bulb having an opening communicating with its interior and surrounded at its outer extremity by an annular lip adapted when the dispensing device is applied to the container to lie against the lip of the container and liquid receiving means connected with the bulb communicating with the interior of the bulb

through said opening therein and adapted when the dispensing device is applied to the container to enter the container through said opening in the container and the liquid receiving means having an opening adjacent its end opposite the bulb communicating with its interior, the bulb passing through said hole in the top of the cap and having a compressible squeezing portion disposed outwardly of the cap to enable drawing of liquid into the liquid receiving means and expelling the same therefrom, said compressible squeezing portion of the bulb being generally cylindrical for the greater part of its extent generally in the direction of its axis and having at least a substantial portion of said generally cylindrical part exposed in a direction transversely of its axis and sufficiently flexible that when squeezed between the fingers it will eject a considerable proportion of its contents and having at its closed end an integral portion of the material thereof which is relatively thin as compared with the material of the generally cylindrical portion of the bulb, said relatively thin portion of the bulb being adapted to be depressed by a finger toward the interior of the bulb and in being so depressed to move inwardly of the bulb for the most part independently of the relatively thick walled portion of the bulb whereby to eject from the bulb upon substantially complete depression of said portion thereof an approximately measured quantity of fluid constituting a comparatively small proportion of the contents of the bulb.

5. In combination, a container such as a bottle or the like having an opening communicating with its interior and surrounded at its outer extremity by an annular lip, a cap fitting over said lip and having a hole in its top, means for fastening the cap to the container, and a dispensing device comprising a hollow bulb having an opening communicating with its interior and surrounded at its outer extremity by an annular lip adapted when the dispensing device is applied to the container to lie against the lip of the container and liquid receiving means connected with the bulb communicating with the interior of the bulb through said opening therethrough and adapted when the dispensing device is applied to the container to enter the container through said opening in the container and the liquid receiving means having an opening adjacent its end opposite the bulb communicating with its interior, the bulb passing through said hole in the top of the cap and having a compressible squeezing portion disposed outwardly of the cap to enable drawing of liquid into the liquid receiving means and expelling the same therefrom, said compressible squeezing portion of the bulb being at least in substantial part exposed to transverse squeezing between the finger and being so designed that when squeezed transversely between the fingers it will eject a considerable proportion of its contents and having at its closed end an integral portion of the material thereof which is relatively thin as compared with the material of the remainder of the compressible squeezing portion of the bulb, said relatively thin portion of the bulb being adapted to be depressed by a finger toward the interior of the bulb and in being so depressed to move inwardly of the bulb for the most part independently of the relatively thick walled portion of the bulb whereby to eject from the bulb upon substantially complete depression of said portion thereof an approximately measured quantity of fluid constituting a comparatively small proportion of the contents of the bulb.

6. In combination, a container such as a bottle or the like having an opening communicating with its interior and surrounded at its outer extremity by an annular lip, a cap fitting over said lip and having a hole in its top, means for fastening the cap to the container, and a dispensing device comprising a hollow bulb having an opening communicating with its interior and surrounded at its outer extremity by an annular lip 5 adapted when the dispensing device is applied to the container to lie against the lip of the container and liquid receiving means connected with the bulb communicating with the interior of the bulb through said opening there-through and adapted when the dispensing device is applied to the container to enter the container through said opening in the container and the liquid receiving means having an opening adjacent its end opposite the bulb communicating 10 with its interior, the bulb passing through said hole in the top of the cap and having a compressible squeezing portion disposed outwardly of the cap to enable drawing of liquid into the liquid receiving means and expelling the same therefrom, said compressible squeezing portion of the bulb being so designed that when squeezed transversely between the fingers it will eject a considerable proportion of its contents and having at its closed end an integral portion so related to the remainder of the compressible squeezing portion of the bulb as to be clearly defined exteriorly of the bulb and 15 being adapted to be depressed by a finger toward the interior of the bulb and in being so depressed to move inwardly of the bulb for the most part independently of the remainder of the compressible squeezing portion of the bulb whereby 20 to eject from the bulb upon substantially complete depression of said portion thereof an approximately measured quantity of fluid constituting a comparatively small proportion of the contents of the bulb.

7. In combination, a container such as a bottle or the like having an opening communicating with its interior and surrounded at its outer extremity by an annular lip, a cap fitting over said lip and having a hole in its top, means for fastening the cap to the container, and a dispensing device comprising a hollow bulb having an opening communicating with its interior and surrounded at its outer extremity by an annular lip adapted when the dispensing device is applied to the container to lie against the lip of the container and liquid receiving means connected with the bulb communicating with the interior of the bulb through said opening therethrough and adapted when the dispensing device is applied to the container to enter the container through said opening in the container and the liquid receiving means having an opening adjacent its end opposite the bulb communicating with its interior, the bulb passing through said hole in the top of the cap and having a compressible squeezing portion disposed outwardly of the cap to enable drawing of liquid into the liquid receiving means and expelling the same therefrom, said compressible squeezing portion of the bulb being so designed that when squeezed transversely between the fingers it will eject a considerable proportion of its contents and having at its closed end an integral portion whose area is not substantially greater than that of the tip of a fore-finger of average size so related to the remainder of the compressible squeezing portion of the bulb as to be clearly defined exteriorly of the bulb and being adapted to be depressed by a finger toward the interior of the bulb and in being so depressed to move inwardly of the bulb for the most part independently of the remainder of the compressible squeezing portion of the bulb whereby to eject from the bulb upon substantially complete depression of said portion thereof and approximately measured quantity of fluid constituting a comparatively small proportion of the contents of the bulb.

tion disposed outwardly of the cap to enable drawing of liquid into the liquid receiving means and expelling the same therefrom, said compressible squeezing portion of the bulb being so designed that when squeezed transversely between the fingers it will eject a considerable proportion of its contents and having at its closed end an integral portion so related to the remainder of the compressible squeezing portion of the bulb as to be clearly defined exteriorly of the bulb and 10 being adapted to be depressed by a finger toward the interior of the bulb and in being so depressed to move inwardly of the bulb for the most part independently of the remainder of the compressible squeezing portion of the bulb whereby 15 to eject from the bulb upon substantially complete depression of said portion thereof an approximately measured quantity of fluid constituting a comparatively small proportion of the contents of the bulb.

8. In combination, a container such as a bottle or the like having an opening communicating with its interior and surrounded at its outer extremity by an annular lip, a cap fitting over said lip and having a hole in its top, means for fastening the cap to the container, and a dispensing device comprising a hollow bulb having an opening communicating with its interior and surrounded at its outer extremity by an annular lip adapted when the dispensing device is applied to the container to lie against the lip of the container and liquid receiving means connected with the bulb communicating with the interior of the bulb through said opening therethrough and adapted when the dispensing device is applied to the container to enter the container through said opening in the container and the liquid receiving means having an opening adjacent its end opposite the bulb communicating with its interior, the bulb passing through said hole in the top of the cap and having a compressible squeezing portion disposed outwardly of the cap to enable drawing of liquid into the liquid receiving means and expelling the same therefrom, said compressible squeezing portion of the bulb being so designed that when squeezed transversely between the fingers it will eject a considerable proportion of its contents and having at its closed end an integral portion whose area is not substantially greater than that of the tip of a fore-finger of average size so related to the remainder of the compressible squeezing portion of the bulb as to be clearly defined exteriorly of the bulb and being adapted to be depressed by a finger toward the interior of the bulb and in being so depressed to move inwardly of the bulb for the most part independently of the remainder of the compressible squeezing portion of the bulb whereby to eject from the bulb upon substantially complete depression of said portion thereof and approximately measured quantity of fluid constituting a comparatively small proportion of the contents of the bulb.

TUNIS J. DYKEMA.
